(57) **CLAIM**

(21) Appl. No.: **29/214,413**

The ornamental design for a handrail for escape routes and flights of steps, with integrated recess for fluoridizing element, as shown and described.

(22) Filed: **Oct. 1, 2004**

DESCRIPTION

(51) LOC (8) Cl. **25-02**

FIG. 1 is a top perspective view of the invention.

(52) U.S. Cl. **D25/38**

FIG. 2 is a top view of the invention

(58) Field of Search D25/38; 256/59,

FIG. 3 is a side view of the invention.

256/63, 64, 65.02, 65.04, 65.05, 65.16

FIG. 4 is a bottom view of the invention; and,

(56) **References Cited**

FIG. 5 is a front view of the invention.
